UNITED STATES PATENT OFFICE.

MYRON B. HAMMOND, OF BRIDGEPORT, CONNECTICUT, ASSIGNOR TO THOMAS P. TAYLOR CO., OF BRIDGEPORT, CONNECTICUT, A CORPORATION OF CONNECTICUT.

MAN'S GARTER.

1,253,686.

Specification of Letters Patent. Patented Jan. 15, 1918.

Application filed November 28, 1917. Serial No. 204,449.

To all whom it may concern:

Be it known that I, MYRON B. HAMMOND, a citizen of the United States, residing at the city of Bridgeport, in the county of 5 Fairfield and State of Connecticut, have invented certain new and useful Improvements in Men's Garters; and I do declare the following to be a full, clear, and exact description of the invention, such as will 10 enable others skilled in the art to which it appertains to make and use the same.

This invention relates to certain new and useful improvements in a garter and it has for its primary aim to provide a permanently closed, encircling band of comparatively great width, said band having stitched throughout its width a non-elastic member constituting a support for a garment clasp.

20 Further, the invention resides in an improved and efficient garter which will properly set and remain in flat engagement about the leg, and one in which the supporting strain is substantially laterally of the leg- 25 encircling band to reduce the longitudinal strain to a minimum and thereby lengthen the wear of the elastic.

The invention further resides in the features of construction hereinafter described 30 and claimed, reference being had to the accompanying drawing wherein—

Figure 1 is an elevation of the improved garter, a portion thereof being taken away;

Fig. 2 is a vertical section on line 2—2 of Fig. 1;

Fig. 3 is a fragmentary elevation of a modified form; and

Fig. 4 is a vertical section on line 4—4 of Fig. 3.

40 With reference to the embodiment disclosed in Figs. 1 and 2, the garter comprises a comparatively wide band 1 of elastic webbing, the ends of which are secured together by a non-elastic strip of fabric 2 that passes up the front over the top edge and down the inner side of the band whereby a permanently closed leg-encircling member is provided. A leather strip 3 incloses the non-elastic connector 2, passing 45 up the front and down the inside of the band with its free ends both depending below the latter. The side edges of this leather strip are stitched, as at 4, to the elastic band outwardly of the fabric strip 2, and the depending ends of said leather

strip are stitched together immediately below the elastic band, as at 5, to leave the freely separable portions 6 between which the garment clasp-supporting strap 7 is secured.

60 The strap or webbing 7 is threaded through the base of the button 8 and passed upwardly over the opposite end and down through the loop element 9 and finally upwardly opposite said first end. These webbing terminals and the intermediate bend adjacent the same are inserted between the terminal portions 6 of the leather strip 3 and secured by stitching, as illustrated.

65 In the form shown in Figs. 3 and 4, a fabric strip 10 is substituted for the leather strip 3, being secured by a stitching 11 and 70 12 in like manner to the stitchings 4 and 5, heretofore described, with the exception that the non-elastic connector strip 13 has its ends extended below the elastic band 1 to be secured by said stitching 12.

75 The fabric strip 10 has its rear length extended, as at 14, to provide a supporting strap or webbing for the button base 8 the former being threaded through the latter and turned upwardly to lie in proximity to the ends of strip 13. The front length is also extended downwardly to support the loop 9 through which it is passed and turned upwardly to lie against the opposite terminal of this strip. These upturned terminals are secured between the front and back lengths of strip 10 by stitching 15, thus 80 providing a simple and secure supporting 85 connection for the garment clasp.

90 In a garter construction as herein described, the elastic webbing is very wide, being substantially three times the width of the elastic band employed in the detachably closed type of garter. This extreme width affords an easy set about the leg without the binding usually experienced with a narrow band. The supporting strain of a 95 sock does not tend to turn either the upper or lower edge of the elastic band since the stitchings 5 and 12 below the latter pass entirely through both clasp supporting straps.

100 Further, it will be noted that the strips 2, 3, 10 and 13 are secured substantially at 105 right angles or transversely of the elastic webbing so that the supporting strain is practically lateral of the webbing, and not longitudinal thereof. Consequently, the life of garter elastic is greatly prolonged. 110

This is accentuated more clearly in Figs. 1 and 3 wherein the upper edges of the ends of the elastic band meet at a very large obtuse angle, closely approaching a straight angle. The strips passing upwardly over the upper edge and down on the opposite side of the elastic band, and being stitched thereto throughout the entire width, securely holds the elastic webbing from puckering or wrinkling.

What is claimed is:

A garter comprising a comparatively wide leg encircling member of elastic material, a non-elastic member consisting of two

downwardly extending portions having 15 straight parallel side edges inclosing the ends of the leg encircling member whereby a permanently closed garter is formed, supporting webbings depending from the said non-elastic member, and clasp members carried by the lower ends of said webbings, said downwardly extending portions being each stitched to the leg encircling member throughout the width of the latter by lines of stitching parallel to the straight side 25 edges.

In testimony whereof I affix my signature.

M. B. HAMMOND.
